CARBURETOR DEVICE

August H. Blattner, St. Louis, Mo., assignor to
 Carter Carburetor Corporation, St. Louis, Mo.,
 a corporation of Delaware

Application June 2, 1936, Serial No. 83,066

5 Claims. (Cl. 261—52)

This invention relates to carburetors for internal combustion engines and consists particularly in novel interconnection control means extending between the choke and throttle valves.

5 In automatic choke carburetors, it is desirable to provide manual means for modifying the position of the choke valve as otherwise determined by thermostatic and/or suction control devices and also means for varying the limiting position 10 to which the throttle valve may be moved either manually or by means of the usual closing spring. When the engine is cold, the choke valve in an automatic choke carburetor is maintained substantially closed by the thermostat so as to provide maximum suction on the fuel nozzles during the cranking and warming periods. Occasionally an over-rich mixture is furnished to the cylinders before the choke valve has opened substantially, due, for instance, to excessive charges 15 from the accelerating pump caused by repeated depressing of the throttle pedal or to sticking of the choke valve. This "loading" may be eliminated if the choke valve is quickly opened, the resulting gust of air serving to clean out the 20 intake system.

When the thermostat becomes heated, the choke valve is held thereby in its full open position so as to constitute a minimum restriction in the air inlet. Occasionally, when the choke and 25 throttle valves are fully open, as, for instance, when a warm engine is subjected to a heavy load and the atmosphere is cold, there may be a tendency for the choke valve to close slightly, causing an undesirable enriching of the mixture. 30 This is due to the low suction in the intake manifold, which is relied upon to draw heated air into the vicinity of the thermostat. It is thus desirable to lock the choke valve in its full open position when the throttle is substantially fully open.

40 The throttle valve is normally urged toward its fully closed position by a spring, but during the warm-up period, the engine oil and grease may be abnormally viscous, particularly in cold weather, and for this and other reasons, it is desirable that 45 the idling speed of the engine be automatically accelerated during this period to prevent stalling.

Fast idle and unloading devices have heretofore been provided, but these have been relatively complicated, unsightly, and expensive to manufacture, or not adaptable to automatic chokes.

An object of the present invention is to provide novel, simplified interconnecting means for carburetor throttle and choke valves.

Another object is to provide means for locking

the choke valve in its full open position when the throttle valve is substantially fully open.

Another object is to provide a choke and throttle interconnection formed substantially of a single linkage arrangement incorporating fast 5 idle and unloading features, and means for locking the choke open when both the choke and throttle valves are fully open.

Another object is to provide a fast idle device having an adjustable unloading element formed 10 as a part thereof.

These objects and other more detailed objects hereafter appearing are attained by the present invention which is characterized substantially by the provision of a fast idle block slidably mounted adjacent the throttle operating lever and having an adjustable, curved, unloading lip for cooperating with the throttle lever to open the choke when the throttle is opened to a predetermined extent. The fast idle block has a lost motion connection with a control lever rigid with the choke valve. The choke lever has a lateral extension positioned to overlie the upper extremity of the link when the choke and throttle are substantially fully open so as to lock the 25 choke.

In the accompanying drawings:

Figure 1 is a side view of a carburetor embodying the invention, the valves being shown in the unloading positions.

Figure 2 is a diagrammatic view showing the choke and throttle valves and inter-connection linkage.

Figure 3 is a view similar to Figure 1, but showing the linkage and valves in a different position, portions of the carburetor being broken away.

Figure 4 is a diagrammatic view showing the linkage and valves in another position.

Figure 5 is a view similar to Figure 3, but showing the choke and throttle valves fully opened, and

Figure 6 is a view of the carburetor taken at 90 degrees to Figures 1, 3 and 5, part of the structure being broken away.

The carburetor illustrated is of the downdraft type including an air inlet horn 1, a mixing chamber 2, and mixture outlet 3 flanged as at 4 for attachment to an engine manifold (not shown). Located in the mixture passage are a series of venturis 5, and a main fuel nozzle 6 opening into the interior of the smallest or primary venturi. An unbalanced choke valve 7 is mounted on pivot 8 in the air horn and a throttle valve 9 is mounted on pivot 10 between the mix-

ing chamber and the mixture outlet. A crank 11 is provided for manually controlling the throttle valve.

Mounted on the outside of the air horn is a housing 12 enclosing a spiral, bi-metallic thermostat 13, the inner portion of which is secured to the choke valve pivot 8. The outer end of the thermostat may be anchored to the cover portion of the housing 12 and the tension on the thermostat 10 stat may be varied by the rotation of the cover. A threaded nipple 14 provides for connecting the thermostat housing with a source of hot air, and suction means preferably will be provided for drawing hot air from a stove 35, conveniently mounted on the engine exhaust manifold 36, through the thermostat housing. The suction means for drawing hot air from the stove 35 may be of any conventional form, however, the pipe 37 is indicated for suitable connection to any 20 conventional source of connection such as the intake manifold.

Formed integral with the carburetor body is a fuel bowl 15 in which is located an accelerating pump generally indicated at 16 for spraying raw 25 fuel into the mixing chamber through nozzle 17 when the throttle is opened.

A rib 18 projecting from the carburetor body adjacent throttle lever 11 slidably mounts the slotted fast idle block 19 by means of a pair of 30 screws 20. The fast idle block has a curved lip 21 which may be conveniently formed of a section of metal bent away from the slotted body portion of the block. Block 19 is pivoted, as at 21a, to a link 22 having a slot 23 in its upper 35 portion loosely receiving a pin abutment 24 projecting laterally from the control arm 25 rigidly mounted on the choke pivot 8 between the air horn 1 and housing 12. Choke lever 25 has a laterally projecting lip abutment 26 at its outer 40 extremity which is adapted to lie above the nub 27 on the upper end of link 22 when both the choke and throttle are full open. A wire spring 28 secured to link 22 as at 29, bears against choke 45 lever pin 24 and constantly urges the same against the inner portion of slot 23. The loose fit between slot 23 and pin 24, and spring 28 cooperate to cause nub 27 to lie well beneath lip 26 in the locked position, as in Fig. 5.

The operation of the device is as follows:

50 The starting positions of the valves are indicated in Fig. 2 in which the choke is held closed by a cold thermostat, and the throttle is partially opened to the position wherein throttle crank 11 just touches but does not raise lip 21 on block 55 19. The fast idle block 19 is in the lowest position, supported by top screw 20, so as to be engaged by throttle screw 32 during clockwise movement of crank 11, to limit closing movement of the throttle to the fast idle position (Fig. 4). 60 With block 19 held between rib 18 and screw 32, block 23 permits opening or breathing of the choke valve, to the extent indicated in Fig. 4, to provide sufficient air during the cranking and warm up periods.

65 In case the mixture supplied during the warm up should become over-rich or the engine become "loaded" for any reason, the choke valve may be manually forced to a partially open position, as indicated in Fig. 1, by moving the throttle lever 70 11 in a counter-clockwise direction beyond the position shown in Fig. 2 so as to cause the cam surface 30 on lever 11 to lift curved lip 21 and linkage elements 19, 22, whereupon the bottom of slot 23 serves as an abutment to engage and 75 rotate pin 24 and open the choke valve. This

causes a gust of air to pass through the carburetor, cleaning out or "unloading" the intake system. For "unloading", the throttle valve need be opened only momentarily. When the throttle is released to be moved by the usual return spring 5 (not shown) to the idling position, block 19 drops and the choke valve closes as determined by the thermostat. Block 19, having less distance to travel than screw 32, will fully drop before the screw reaches stop rib 18, thus again limiting 10 closing of the throttle to the fast-idle position. The unloading interconnection is also useful to prevent excessive enrichment or "heaviness", as frequently discovered during dynamometer testing, in case the throttle is substantially opened 15 before the engine is fully warmed.

During the cranking and warm up periods, the thermostatically controlled choke will act as an air valve, fluctuating under the influence of varying suction in the carburetor, this movement being permitted by the lost motion connection between choke lever 25 and link 22, even though block 19 is held as in Fig. 4. As the thermostat becomes heated, pin 24 engages the upper edge of slot 23, as shown in Fig. 3, and, if block 19 is released from screw 32, lifts the block from the fast-idle position, as in Figs. 3 and 5. In this position of the parts, the throttle valve may be fully closed to the normal idling position with throttle screw 32 engaging rib 18 (see Fig. 3), 30 and the choke valve will eventually be moved by the thermostat to its full open position, as in Fig. 5, and will ordinarily remain in this position until the thermostat is again closed.

When the throttle is moved to its fully open 35 position, linkage 19, 22 will be lifted to its uppermost position, and held in this position due to engagement between the lip 21 on block 19 and cam surface 30 on the throttle lever. As the choke valve is fully opened by the thermostat, 40 finger 26 on choke arm 25 is permitted to pass around nub 27 due to looseness between slot 23 and pin 24, and the nub is urged outwardly with respect to pin 24 by spring 28 to insure locking alignment of elements 26 and 27. Spring 28 also 45 prevents rattling. In the latched or locked position of the parts, choke lever 25 cannot be rotated counterclockwise to close the choke valve as long as linkage 19, 22 is held in its upper position by the throttle lever 11. The choke valve will be 50 locked in this manner, as distinguished from the partially opened "unloading" position shown in Fig. 1, only when the choke has been fully opened by the thermostat and the throttle is also fully opened. Thus two different positions of the choke 55 are provided in each of which it is locked against closing, both requiring substantial opening of the throttle valve, but the throttle valve can force the choke only to the "unloading" position in Fig. 1. When lever 11 is again rotated clockwise 60 to close the throttle valve after the thermostat is heated, linkage 19, 22 will be supported in its upper position by the choke valve lever. When the thermostat cools, the choke can substantially 65 fully close, even though block 19 in its descent should engage the upper edge of screw 32.

Link 22 is provided with a restricted, crimped portion 30 for adjusting the length of the linkage to insure that fast idle block 19 is rendered inoperative at the proper time relative to the position 70 of the choke valve. Unloading lip 21 is also bendable for adjustment purposes. Adjusting means 30 is more fully disclosed and claimed in a co-pending application, Serial No. 80,736, filed May 20, 1936, in the name of Fred A. Kommer. Inter- 75

connection mechanism, similar in some respects to the corresponding parts described above, is disclosed and claimed in copending applications, Serial No. 666,118 filed April 14, 1933, in the names of George M. Bicknell and Otto Henning, and Serial No. 89,088, filed July 6, 1936, in the name of the present inventor. Other features are claimed in a copending application, Serial No. 666,118, filed April 14, 1933, in the names of George M. Bicknell and Otto Henning.

The linkage arrangement described is simple and economical to manufacture and effectively modifies the functioning of the choke and throttle valves as required for the fast idle, unloading, and open choke locking conditions. The carburetor parts shown are not essential and various features of the invention may be applied to other types of carburetors, whether of the manual or automatic choke variety and whether having downdraft, updraft, or horizontal mixture passages. Moreover, the interconnecting arrangement itself may be modified in various respects as will occur to those skilled in the art and the exclusive use of all such modifications as come within the scope of the appended claims is contemplated.

I claim:

1. A link for use in a carburetor having choke and throttle valves, said link comprising a sheet metal member having a recess at one end whereby it may be pivotally connected to an adjacent element and having an opening at the other end adapted to loosely receive a connecting pin, said link being provided with a pair of slitted and bent portions between said recess and said opening, one of said portions serving for adjusting the length of said link, and a spring member mounted in the other of said slitted and bent portions and having one end disposed adjacent said opening for taking up lost motion between said opening and a connecting pin therein.

2. In a carburetor, choke and throttle valves, pivoted control levers for said valves, intercon-

nection linkage having a pin and slot lost motion connection with the choke lever and an abutment structure adjacent said throttle lever for engagement thereby when said throttle valve is opened to move said linkage, said choke valve being capable of opening and closing movements independently of said linkage when said throttle valve is opened, said choke lever including a lateral lip spaced outwardly beyond the pin and slot connection, and said interconnecting linkage having an abutment disposed to underlie said lateral lip when said choke valve is substantially fully opened, and a spring device for causing said linkage to interlock with said choke lever when both of said valves are substantially fully open to prevent closing of said choke valve.

3. In a device of the class described, a carburetor structure including a choke valve, a thermostat for controlling said choke valve, a throttle valve, a source of heat, means including a passageway connected to the carburetor posterior to the throttle for transferring heat from said source to said thermostat, a throttle operating member, a choke operating member, a link movable by one of said members and having an abutment to engage the other of said members, said other member having a portion adapted to be engaged by said abutment when both valves are open to prevent closing of the choke valve while the throttle remains in open position.

4. A device of the character described in claim 3 and further including a connection operative by the throttle when the choke is in substantially closed position to insure the movement of the choke valve to an only partially open position when the throttle valve is completely opened.

5. A device of the character described in claim 3 and further including a member operable by a full opening movement of the throttle valve for insuring the opening of said choke valve at least to a predetermined partially opened position.

AUGUST H. BLATTNER.
